Primary Examiner — Philip S Hyder*(74) Attorney, Agent, or Firm* — Brad C. Spencer(57) **CLAIM**

The ornamental design for a welding torch handle, as shown and described.

DESCRIPTION

FIG. 1 is a front perspective view of the design for a welding torch handle;

FIG. 2 is a right side view thereof;

FIG. 3 is a front view thereof;

FIG. 4 is a rear view thereof;

FIG. 5 is a left side view thereof;

FIG. 6 is a top plan view thereof;

FIG. 7 is a bottom plan view thereof; and,

FIG. 8 is a rear perspective view thereof.

The broken lines depict portions of the welding torch handle in which the design is embodied that form no part of the claimed design.

1 Claim, 7 Drawing Sheets(56)
